CLOCKCASE OR SIMILAR ARTICLE

Joseph Gottlieb, Jersey City, N. J.

Application January 20, 1954, Serial No. 28,601

Term of patent 7 years

(Cl. D42—7)

To all whom it may concern:

Be it known that I, Joseph Gottlieb, a citizen of the United States, residing at Jersey City, in the county of Hudson and State of New Jersey, have invented a new, original, and ornamental Design for a Clockcase or Similar Article, of which the following is a specification, reference being had to the accompanying drawing, forming a part thereof.

Fig. 1 is a front elevational view of a clockcase or similar article, showing my new design.

Fig. 2 is a side elevational view thereof.

Fig. 3 is a top plan view thereof.

Fig. 4 is a transverse sectional view taken along line 4—4 of Fig. 2.

Fig. 5 is a fragmentary view taken along line 5—5 of Fig. 3.

The dominant feature of the design resides in the portions shown in full lines.

I claim:

The ornamental design for a clockcase or similar article, substantially as shown and described.
